HAT SWEAT SEWING ATTACHMENT

Orland B. Reid, Kenilworth, N. J., assignor to
The Singer Manufacturing Company, Elizabeth, N. J., a corporation of New Jersey

Application April 21, 1949, Serial No. 88,761

9 Claims. (Cl. 112—136)

1

This invention relates to attachments for sewing machines and more particularly to an attachment for guiding the component elements of a waterproof hat sweat to the stitch forming mechanism of sewing machines having an interrupted feed and a laterally vibrating needle, such, for example, as the "Singer" No. 107W9 machine which produces, in each cycle, one straightaway stitch and two transverse stitches.

The invention has as its primary object to provide an attachment which will so present to the stitch-forming mechanism of a machine of this nature, a leather sweatband and a previously united reed, reed-cover-strip and a protector strip of waterproof material, that one of the two flaps of the reed-cover-strip will be united to one marginal portion of the sweatband without the possibility of the needle puncturing the waterproof strip or the usual bead which encloses the reed.

The previously united reed, reed-cover-strip and the strip of waterproof material, which this attachment is designed to handle, is the product of the electronic seaming machine which forms the subject of the pending United States patent application of O. B. Reid, Serial No. 55,513, filed October 20, 1948.

Another object of the invention is to provide, in an attachment of this nature, improved means for guiding one edge of the leather sweatband substantially into contact with the base of the bead, comprising the usual reed and its covering strip, and means for deflecting the bead proper to one side and holding it out of the path of reciprocation of the needle to prevent the needle from contacting the bead.

Another object is to provide, in an attachment as above described, a guide for the leather sweatband which will accurately hold one edge of the sweatband relative to the needle so that when the needle is reciprocated in one of its two lateral positions, in which it makes its depth stitch, it will penetrate the sweatband and one flap of the reed-cover-strip and when reciprocated in its other lateral position, in which it makes its edge stitch, it will just miss the edge of the sweatband and will penetrate only the flap of the reed-cover-strip.

Still another object is to provide an attachment of this nature in which the sweatband guide is automatically adjustable and is capable of adapting itself to varying widths and curvatures of sweatbands.

With the above and other objects in view, as will hereinafter appear, the invention comprises

2

the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings

Fig. 1 is an end elevation of a portion of a sewing machine fitted with the present improved attachment carrying the component elements of a waterproof hat sweat.

Fig. 2 is a plan view of the parts shown in Fig. 1 with the needle-bar omitted and the needle shown in section.

Fig. 3 is a view in elevation looking from the right in Fig. 1.

Fig. 4 is an enlarged vertical section taken substantially on the lines 4—4 of Figs. 1 and 2.

Fig. 5 is an enlarged vertical section taken substantially on the lines 5—5 of Figs. 1 and 2.

Fig. 5a is an under side view of a presser-plate and a pair of guide blocks adjustably secured thereto, hereinafter described.

Fig. 6 is an enlarged vertical section taken substantially on the line 6—6 of Figs. 1 and 2.

Fig. 7 is a bottom view of the automatically adjustable guide for the leather sweatband, with the supporting shank of the guide broken off.

Referring more specifically to the drawings, this invention is disclosed as embodied in an attachment comprising a base-plate B adapted to be adjustably secured upon the cloth-plate C of a sewing machine by screws 1 passing through a slot 2 in the base-plate and threaded into the cloth-plate. The sewing machine to which the present attachment is particularly adapted also includes a vertically reciprocating and laterally vibrating needle-bar 3 carrying, at its lower end,

an eye-pointed thread-carrying needle 4 which is designed to cooperate with a conventional lower loop-taker mechanism, not shown, in the formation of edge and depth stitches. Fitted into the cloth-plate, in the region of the stitch forming mechanism, is a throat-plate T having slots 5 (Fig. 6) through which operates a feed-dog forming a part of a work-feeding mechanism, not shown. This feeding mechanism is adapted so to advance the work through the machine that after

each forward feed of the work and the making of an edge stitch the work is held stationary while the needle-bar and the needle carried thereby are moved laterally to the left and reciprocated to form a first offset, or depth stitch in the work perpendicular to the line of feed and then moved

laterally to the right and again reciprocated to form a second offset stitch parallel to the first offset stitch. This makes a well known form of seam which is commonly used in attaching sweatbands to reed-cover-strips.

The work which this attachment is designed to handle comprises a leather sweatband S, a reed-cover-strip P, having a central hollow bead portion b, enclosing a reed R, and oppositely disposed flaps f¹ and f², and a strip of waterproof material M having one edge portion bonded between the flaps f¹ and f² of the strip P, as shown in the above mentioned United States patent application of O. B. Reid.

The work is held down upon the throat-plate T and in position to be engaged by the feeding mechanism by a presser-foot 6 carried by a spring-depressed presser-bar 7.

As shown most clearly in Figs. 2 and 6, the presser-foot is formed with a transverse slot 8 for the passage of the reciprocating and vibratory needle 4 and, in its under side, with a longitudinal groove 9 (Fig. 6) for the passage of the bead b of the strip P.

Movably mounted on vertically disposed studs 10 and 11, secured to and extending upwardly from the attachment base-plate B, is a presser-plate 12 on the under side of which are adjustably mounted, as by screws 13 and 14 passing through slots 15 and 16, a pair of spaced guide blocks 17 and 18, (see Figs. 5 and 5^a). The adjacent ends of these guide blocks are beveled upwardly and outwardly, as indicated at 17^a and 18^a. Above the space between the ends of the guide blocks the under side of the presser-plate 12 is formed with a downwardly open channel 19. Thus the wall of the channel 19 and the proximate ends of the guide blocks 17 and 18 afford a bell-mouthed upwardly flaring guideway for the bead b and the adjacent neck portion n of the reed-cover-strip P, while the blocks 17 and 18 bear downwardly upon the flaps f¹ and f² to smooth and slightly tension the reed-cover-strip.

Beehive springs 20 surrounding the studs 10 and 11 between the presser-plate 12 and pressure-adjusting nuts 21, threaded on the studs, exert a yielding downward pressure on the plate 12 and blocks 17 and 18. By adjusting the nuts the pressure on the flaps f¹ and f² may be varied.

The leather sweatband S passes through a guide H comprising a supporting shank 22 pivotally mounted on a threaded upright stud 23 carried by the base plate B. The shank is formed with an aperture 24 which receives the head of a locating pin 25 carried by the base plate B to hold the shank and the parts carried thereby in operative position. A beehive spring 26 surrounding the stud 23, between the shank 22 and a nut 27 threaded on the stud, normally serves to hold the shank depressed to maintain the pin 25 in the aperture 24 but permits raising of the shank to clear it of the pin 25 after which the shank and the parts carried thereby may be turned about the axis of the stud 23, as indicated in dotted lines in Fig. 2, to remove the sweatband guide H from operative position. The shank 22 has a raised portion 22^a upon which is adjustably secured, by screws 28, the foot portion 29^a of a normally fixed edge guide 29 comprising the overturned edge portion 29^b of a sweatband supporting plate 30. The guide 29 engages one edge of the leather hat sweat S and so positions it that, in the lateral position of the needle in which it makes an edge stitch, the needle just barely misses the edge of the hat sweat and

pierces only the flap f¹ of the reed-cover-strip. When reciprocated in its other lateral position to make a depth stitch the needle will penetrate both the hat sweat and the flap f¹.

5 The opposite edge of the hat sweat S is engaged by an automatically adjustable edge guide comprising the overturned edge portion 31^a of a plate 31 slidably mounted at the under side of the sweatband supporting plate 30 within inturned end portions 30^a and 30^b of the plate 30 (Fig. 7). At the upper side of the sweatband guide the overturned portion 31^a slides beneath the free end portion of a guide plate 32 secured, at one end, as by soldering, to the portion 29^b of the fixed edge guide.

The plate 31 and the edge guide 31^a carried thereby are normally urged toward the edge guide 29^b by a spring 33 having its opposite ends connected to ears 34 and 35 secured to and depending, respectively, from the plates 30 and 31. This insures that the right hand edge of the sweatband S will be held in contact with the edge guide portion 29^b and thereby properly aligned relatively to the path of reciprocation of the needle. A stop block 36 secured to the under side of the plate 30 limits the movement of the plate 31 under the influence of the spring 33. The plate 31 and the edge guiding portion 31^a carried thereby are free to be moved to the left, in opposition to the spring 33, to accommodate sweatbands of various widths and curvatures.

As hereinbefore stated it is desirable, in making the stitches along the right hand edge of the leather hat sweat and through the flap f¹ only, that the needle penetrate the flap closely adjacent the bead b without contacting the bead and without penetrating the strip of waterproof material M. This is effected by deflecting the bead out of the path of the needle immediately in advance of and adjacent the needle. The means for accomplishing this includes a guide blade 37 (Figs. 2 and 4) secured upon the under side of a plate 38 adjustably secured by screws 39 to the base plate B. The forward free edge 45 of the blade 37 overlies the flap f² and engages the neck n below the bead b, at that side of the bead remote from the needle, as seen most clearly in Fig. 4. Cooperating with the guide blade 37 is a deflector plate 40 adjustably secured upon the 50 upper side of the plate 38 by screws 41. The outer free end of this plate is turned downwardly as at 42 (Fig. 4) and engages the bead b at the side thereof adjacent the needle. The plate 40 is so adjusted on the plate 38 and relative to the 55 blade 37 that the bead b, the neck n and the edge of the sheet M within the neck are deflected and held out of the path of reciprocation of the needle so that the needle in its descent will just miss the bead and the sheet M.

60 As shown in Figs. 2, 4 and 7, the side wall 29^b of the fixed edge guide 29 is cut away at its delivery end as indicated at 29^c. This affords sufficient clearance to permit the sweatband to contact the downturned end 42 of the bead deflector plate 40 even when the sweatband is of slightly curved form.

From the foregoing it will be apparent that this invention has provided a hat sweat sewing attachment which will guide reed-cover strips and sweatbands of various widths and curvatures to the stitch forming mechanism of a sewing machine so that the reciprocating and laterally vibrating needle will make depth stitches through one edge portion of the sweatband and through one flap of the reed-cover-strip and edge stitches

through the flap only, closely adjacent the edge of the sweatband. Likewise, it will be apparent that the means provided for deflecting the bead and its neck away from the needle will insure against penetration of the bead and the water-proof material M by the needle.

Having thus set forth the nature of the invention, what I claim herein is:

1. A hat sweat sewing attachment for a sewing machine having stitch forming mechanism including a reciprocating and laterally vibrating needle, comprising a sweatband guide constructed and arranged to guide a sweatband so as to be missed by the needle when the needle is reciprocated in that one of its two lateral positions in which it makes an edge stitch and to be pierced by the needle when it is reciprocated in its other lateral position in which it makes a depth stitch, a guide for a reed-cover-strip having an upstanding bead and flaps projecting oppositely from said bead, said reed-cover-strip guide being located below said sweatband guide and comprising a guideway for said bead and a pair of members extending oppositely from said guideway and overlying said flaps to guide a reed-cover-strip to the stitch forming mechanism with the upstanding bead substantially engaging that edge of the sweatband adjacent the needle and with one flap beneath the sweatband, and bead-deflecting means including a member bearing laterally upon said bead at the side thereof adjacent the needle to deflect said bead laterally and to hold it out of the path of reciprocation of said needle when making said edge stitch.

2. A hat sweat sewing attachment for a sewing machine having a cloth plate and stitch forming mechanism including a reciprocating and laterally vibrating needle, comprising a base-plate secured upon said cloth plate, a sweatband guide mounted on said base plate and constructed and arranged to guide a sweatband so as to be missed by the needle when the needle is reciprocated in that one of its two lateral positions in which it makes an edge stitch and to be pierced by the needle when it is reciprocated in its other lateral position in which it makes a depth stitch, a spring-depressed guide for guiding and tensioning a reed-cover-strip having an upstanding bead and flaps projecting oppositely from said bead mounted on said base plate and located below said sweatband guide, said guide for the reed-cover-strip being located below said sweatband guide and comprising a guideway for said bead and a pair of pressure members bearing upon the oppositely projecting flaps of said reed-cover-strip, said guideway acting to guide a reed-cover-strip with the upstanding bead substantially engaging that edge of the sweatband adjacent the needle and with one flap beneath the sweatband, and bead-deflecting means including a member engaging said bead immediately forwardly of the needle and at the side of the bead adjacent the needle to deflect said bead laterally and to hold it out of the path of reciprocation of said needle when making said edge stitch.

3. A hat sweat sewing attachment for a sewing machine having a cloth plate and stitch forming mechanism including a reciprocating and laterally vibrating needle, comprising a base plate secured upon said cloth plate, a sweatband guide constructed and arranged to guide a sweatband so as to be missed by the needle when the needle is reciprocated in that one of its two lateral positions in which it makes an edge stitch and to be pierced by the needle when it is recip-

located in its other lateral position in which it makes a depth stitch, a spring-depressed presser plate mounted on said base plate below the sweatband guide and having a channel on its underside, a pair of spaced guide blocks carried by said presser-plate at opposite sides of said channel, said channel and the adjacent ends of said guide blocks affording guide means for the upstanding bead of a reed-cover-strip passed beneath said presser-plate, to guide a reed-cover-strip with the upstanding bead substantially engaging that edge of the sweatband adjacent the needle and with one flap beneath the sweatband, and bead-deflecting means including a member engaging the bead at the side thereof adjacent the needle to deflect said bead laterally and to hold it out of the path of reciprocation of said needle when making said edge stitch.

4. A hat sweat sewing attachment as defined in claim 1 in which the sweatband guide is yieldable widthwise to permit it to adapt itself to sweatbands of various widths and curvatures.

5. A hat sweat sewing attachment as defined in claim 1 in which the sweatband guide comprises a fixed edge guide constructed and arranged to guide one edge of the sweatband in a line between the two extreme lateral positions of the needle, an opposed laterally movable edge guide constructed and arranged to engage the opposite edge of the sweatband, and spring means normally biasing the last named edge guide toward the fixed edge guide to maintain one edge of the sweatband in contact with the fixed edge guide.

6. A hat sweat sewing attachment as set forth in claim 2, in which the sweatband guide comprises a spring depressed shank pivotally mounted on the base plate; in which separable interlocking means are provided for detachably securing the shank to the base plate with the sweatband guide in operative position; and in which the sweatband guide includes relatively adjustable edge guides for the sweatband and spring means for normally urging one of said edge guides toward the other.

7. A hat sweat sewing attachment, as set forth in claim 2, in which the guide for the reed-cover-strip comprises a spring depressed presser plate slidably mounted on vertically disposed studs carried by the base plate and formed on its underside with a guide channel, and in which a pair of guide blocks are secured to the presser plate at opposite sides of said guide channel, said guide channel and guide blocks being so constructed and arranged as to form a guide for the upstanding bead of a reed-cover-strip, said guide blocks also serving as pressed members for the oppositely extending flaps of the reed-cover-strip.

8. A hat sweat sewing attachment as set forth in claim 1 in which the bead-deflecting means includes a guide blade engaging the neck of the bead at that side thereof remote from the needle, and a cooperating deflector plate which extends over the bead and engages the bead at the side thereof adjacent the needle to deflect the bead laterally out of the path of reciprocation of the needle.

9. A hat sweat sewing attachment as set forth in claim 2 in which the bead-deflecting means includes a guide blade adjustably mounted on the base plate and having an edge engaging the neck of the bead at that side thereof remote from the needle and a cooperating deflector blade adjustably mounted on said guide plate and which extends over said bead and has a down-

turned portion engaging the bead at the side thereof adjacent the needle to deflect the bead laterally out of the path of reciprocation of the needle.
